W. A. Whiting,
Cutting Shingles.
Patented Feb. 3, 1857.

N° 16,562.

UNITED STATES PATENT OFFICE.

WILLIAM A. WHITING, OF ST. LOUIS, MISSOURI.

SHINGLE-MACHINE.

Specification of Letters Patent No. 16,562, dated February 3, 1857.

To all whom it may concern:

Be it known that I, WILLIAM A. WHITING, of the city of St. Louis and State of Missouri, have invented a new and Improved 5 Shingle-Machine; and I do hereby declare that the following is a full and exact description thereof, reference being had to the accompanying drawings, making a part of this specification, Figure 1 being a side elevation, and Fig. 2 a vertical section, of said machine.

Similar letters indicate like parts in both figures of said drawings.

Shingles produced by the process of riveting or cleaving from blocks softened by steam, in machines heretofore in use, have been of inferior quality, for the reason that they are badly "checked" as it is technically termed, or filled with oblique cracks, caused 10 by partially tearing asunder the fibers of wood as they yield before the edge of the cleaving knife. By experimenting with this description of shingle machines, I have discovered that by placing layers *e*, of india 15 rubber, or other equivalent elastic substance, under the rest *c*, thereof, which supports the steamed blocks while they are being converted into shingles, the shingles cut therefrom are perfectly sound in every respect— 20 25 30 35

of the knife-wheel *a*, and by placing washers of the same material under the screw nuts *f*, *f*, of the screw bolts *m*, *m*, which secure the said bearing boxes to the sides of the machine. Or if preferred, the elastic material may be placed both under the rest *c*, and under the bearings of the knife-wheel *a*, of the machine. The entire machine may also rest upon elastic bearings *j*, *j*, as shown in 40 45 the drawings.

In the accompanying drawings *g*, *i*, are the side beams and *h*, *h*, are the uprights of the frame of the machine.

k, *k*, are shoes placed under the side beams 50 *i*, *i*, and secured thereto by the screws *l*, *l*.

The principle of my invention, viz., giving an elastic bearing to the rest, or giving an elastic bearing to the knives or their supporters, may be applied to all machines employed for forming shingles, staves, or other articles, from steam-softened wood.

Having thus fully described my improved shingle machine, what I claim therein as my invention and desire to secure by Letters 60 Patent, is—

Giving an elastic bearing to its rest *c*, or to the bearing boxes of the knife wheel, or to the equivalents thereof, for the purpose herein described.

The above specification of my improved shingle machine, signed and witnessed this 65 10th day of December, 1856.

WILLIAM A. WHITING.

Witnesses:

JOSEPH W. CORD,
H. ROBINSON.
